MICROWAVE POWER DIVIDER AND SWITCH

John F. Zaleski, Valhalla, N. Y., assignor to General Precision Laboratory Incorporated, a corporation of New York

Application December 29, 1951, Serial No. 264,095

6 Claims. (Cl. 333—7)

1

This invention pertains to microwave power dividers and to microwave switches.

The principal requirements for a microwave power divider include low impedance discontinuity at all power ratios and low power leakage to the cut-off arm in the terminal positions. Division of the input into two outputs in any ratio should be readily effected by a single, simple and continuous adjustment. The divider should be broadband and have a voltage breakdown limit not materially lower than that for a comparable straight length of hollow guide. The design should have no critical interdependent dimensions. A microwave switch in addition to most of these requirements must have low inertia moving parts for rapid switching through a relatively small arc between its terminal positions.

The microwave device of this invention has these characteristics, so that it may be applied equally well in the design of a power divider or of a switch. It is suitable for employment with the commonly used type of microwave transmission line composed of hollow rectangular guide and briefly consists of a section of rectangular hollow guide to which microwave energy can be applied, and a second similar hollow guide attached at a midpoint to the first in a T connection, its two ends serving as the two output connections. A 90° rotor and shaft provide adjustment of the output ratio when the device is used as a power divider and the shaft is operable at high speed between its extreme positions when the device is used as a microwave switch.

One object of this invention then is to provide a microwave hollow guide power divider that can also be used as a microwave switch.

Another object is to provide a microwave rectangular hollow guide power divider that is wideband and is efficient in all positions of adjustment.

Still another object is to provide a microwave rectangular hollow guide switch that has only 90° motion between its two switched positions.

A further understanding of the invention may be secured from the following detailed description together with the associated drawings, in which:

Figure 1 depicts an embodiment of the invention.

Figures 2 and 3 are cross-sections of Fig. 1 taken on the planes 2—2 and 3—3 respectively.

Figure 4 is a cross-section of Fig. 1 taken on the plane 3—3 showing the rotor in its intermediate position.

Referring now to Fig. 1, a rectangular hollow microwave guide 11 short-circuited by a conduc-

2

tive plate 12 at one end is arranged for excitation at the other end by microwave energy. The excitation source is schematically indicated by the microwave generator 13. Another rectangular hollow microwave guide 14 of similar size is joined at right angles to the guide 11, the two guides being interconnected by a rectilinear box 16, the box serving to provide space for an operating shaft 17 and its associated choke bearing 18. This construction brings the plane of the lower broad side of guide 11 parallel to the plane of the upper broad side of guide 14 but separated therefrom by the length of the box 16. The guide 14 should be loaded at its two ends 19 and 21 by utilizing apparatus having impedance equal to the guide characteristic impedance to avoid reflections, in accordance with standard practice.

The junction of the guides 11 and 14 includes an aperture in the lower broad side of the guide 11, the interior space of the box 16 and an aperture in the upper broad side of the guide 14, so that the passage provides access from the field space within the hollow guide 11 to the field space within the hollow guide 14. The junction has a square cross-sectional area in the plane of the line 2—2, the length of one side being equal to the larger cross-sectional dimension A, Fig. 2, of the hollow guide. This is the maximum value that either side of the area can have although either or both sides can be smaller as will be explained later.

The distance from the end plate 12, Fig. 1, to the center line 22, Fig. 2, of the junction area is approximately $\lambda_g/4$, λ_g being the wavelength in the guide of the energy supplied to the guide 11 by the microwave generator 13, to produce the maximum transfer of energy from guide 11 to guide 14. This distance, however, departs from the exact value of $\lambda_g/4$ by an amount sufficient to match out the junction discontinuity.

The shaft 17, Fig. 2, bisects the area of the aperture and is journaled in two conventional choke bearings 18 and 23, although it may alternatively be journaled in the single bearing 18 and terminated near but not touching the side 24 of the square aperture.

Two conductive rods 26 and 27, positioned at right angles as respects each other are secured at one end thereof to the shaft 17 and extend normal thereto from a point midway at the transverse dimension of the wave guide 14. These rods are made of such a length as to just clear the sides 28 and 29 of the aperture and the lower broad side 30 of the wave guide 14 when rotated by the shaft 17.

The shaft 17 acts to divide the aperture defined

by the sides 24, 28, 29 and 31, Fig. 2, into two equal orifices, each of which will support microwave transmission in only the dominant mode. One orifice is defined by the shaft 17 and the aperture sides 24, 28 and 31, and the other orifice is defined by the shaft 17 and the aperture sides 24, 29 and 31.

The rods 26 and 27 act selectively to interdict the orifices to microwave energy. This occurs when either rod spans either of the orifices because a rod, in so spanning the orifice, divides it into two equal spaces, neither of which is large enough to support the applied microwave energy in any mode. A rod of this character thus serves substantially the same purpose as a solid metal shield in preventing the passage of microwave energy through an orifice of this size.

When an orifice such as that defined in Fig. 2 by the shaft 17 and sides 24, 28 and 31 is left open, that is, unspanned by either rod, the open oblong orifice constitutes a longitudinal slot in a broad side of the guide 11, displaced from its longitudinal center line, its length being equal to the dimension A and its width being less than one-half A by the amount of the radius of the shaft 17. However, the width may be made as small as desired although the coupling coefficient will decrease with the width. Such an orifice or slot has the property of radiating microwave energy out of the guide and the discontinuity which it presents to the source can be matched out almost completely by a suitable matching device. Such a matching device is constituted by the end plate 12, which is placed at a distance from the orifice midpoint departing from $\lambda_{g/4}$ by an amount sufficient to match out the impedance discontinuity.

The oblong orifice can also be considered as constituting a series opening as respects the guide 14. Such a series opening couples energy to the guide if the length of the opening, which lies transversely across the guide, is greater than the cutoff value of the dimension A, for the applied frequency, this cutoff dimension being approximately one-half of the wavelength in free air of the applied energy. Any impedance discontinuity presented by this series opening is matched by the previously mentioned departure of the spacing of the end plate 12 from a distance of $\lambda_{g/4}$.

In operation, microwave energy is applied from the generator 13 to the guide 11. The shaft 17 is so positioned as to cause the rods 26 and 27 to assume the positions shown in Fig. 3. The microwave energy then is coupled through the orifice defined by the shaft 17 and apertured sides 24, 28 and 31 to the guide 14. There the energy is prevented from passing toward the right as seen in Fig. 3 by the rod 27, which interdicts the right arm 14' of guide 14. The microwave energy therefore passes out through only the left arm 14" of the guide 14. Leakage to the right past rod 26 will not be in phase with leakage to the right past rod 27 and therefore these two leakages will not be directly additive and will to some extent cancel each other. Such leakage as remains is minimized by reducing the rod clearances and the net effect is easily reduced sufficiently to provide 25 db decoupling between the two arms of guide 14.

When shaft 17 is rotated 90° clockwise the rod 27 is brought into the dashed position 32, Fig. 3, and the rod 26 is brought into the vertical position formerly occupied by rod 27. The orifice defined by the shaft 17 and aperture sides 24, 28 and 31 is then interdicted and microwave energy passes out the other orifice only into arm 14' of guide 14.

This power divider presents a relatively low impedance discontinuity to the input arm at all positions of the shaft 17. As an example of operation at an intermediate position, Fig. 4 illustrates the power divider adjusted to divide the input power into two equal outputs, the rods 26 and 27 being in their midpositions. The microwave energy then passes from guide 11 into the left arm 14" through an area defined in its lesser dimension by the perpendicular distance from the rod 27 to the edge 28 of the junction aperture. The impedance of such an area exposed to microwave energy as described is in direct relation to the magnitude of this dimension, and is in this case less than the characteristic guide impedance. Similarly, microwave energy passes from guide 11 into the right arm 14' through a similar area defined by the gap between the rod 26 and the edge 29 of the aperture, this area also presenting an impedance less than the characteristic guide impedance. But since these two impedances are effectively in series as presented to the source, their sum has a magnitude roughly equal to that characterizing the guide. Therefore, in this midposition, and it is found to be true also at all other positions of the rods 26 and 27, only a small impedance discontinuity is presented to the microwave energy source.

The device can also be employed as a microwave switch, in which use the device is especially valuable because it has but one moving part, its throw is only 90°, its rotating parts can be made to have very low inertia, and because the impedance discontinuity during switching is minimized. In order to operate the power divider as a switch it is merely necessary to connect the shaft 17 to manual or other means for moving it from one terminal position to the other, such means being schematically indicated in Fig. 2 by the crank and handle 33.

What is claimed is:

1. A device of the class described comprising, a first rectangular hollow wave guide having an input terminal at one end adapted to be connected to a source of microwave energy and having the other end reflectively terminated, a second similar wave guide having its broad sides parallel to the broad sides of said first wave guide and having two arms containing ends adapted for use as output terminals, said second wave guide being connected intermediate said two ends in overlapped relation to said first wave guide adjacent said other end thereof to form a T junction, means defining an aperture in the overlapped areas joining the interior spaces of said first and second wave guides, said aperture having a length in a direction transverse to said second wave guide such that the full length thereof will transmit applied microwave energy while substantially less than the full length thereof will prevent the transmission of such energy in any mode, a rotatable shaft parallel to said first wave guide and dividing said aperture into two equal windows, and a pair of equal length rods secured normally to said shaft and normally to each other intermediate the sides of said aperture to extend into one or the other of said windows and to extend into one or the other of said arms respectively in accordance with their positioning by said shaft, thereby controlling the impedance of said windows and arms to microwave energy.

2. A device of the class described comprising, a first rectangular hollow guide having an input terminal at one end adapted to be connected to a source of microwave energy, a second similar wave guide having its broad sides parallel to the broad sides of said first wave guide and having two arms containing ends adapted for use as output terminals, said second wave guide being connected intermediate said two ends in overlapped relation to said first wave guide to form a T junction, means defining a rectangular aperture in the overlapped areas joining the interior spaces of said first and second wave guides, said aperture having a length in a direction transverse to said second wave guide such that the full length thereof will transmit applied microwave energy while substantially less than the full length thereof will prevent the transmission or such energy in any mode, a transverse metal plate terminating the other end of said first wave guide parallel to the center plane of said aperture and at a distance therefrom approximately equal to an odd quarter of the wavelength of said energy in the guide, a rotatable conductive shaft parallel to said first wave guide and dividing said aperture into two equal windows, a pair of equal length conductive rods secured normally to said shaft and to each other and lying in said center plane, means for rotating said shaft into one position to extend one said rod into one of said windows and the other said rod into the interior space of said two arms, and into one other position to extend the other said rod into the other of said windows and the one said rod into the interior space of said two arms, thereby controlling the admittance of said windows and said arms to microwave energy.

3. A device of the class described in accordance with claim 2 in which said rectangular aperture has maximum length and width equal to the greater internal cross sectional dimension of the guide and in which the limiting minimum dimension of said rectangular aperture parallel to said first guide is equal to one-half of the wavelength of said applied microwave energy in free space.

4. A device of the class described in accordance with claim 2 in which said connection between the first and second guides comprises a short rectangular hollow guide separating the first and second guides by its length and the walls thereof supporting said shaft.

5. A microwave power divider comprising, a first rectangular hollow guide having an input terminal at one end adapted to be connected to a source of microwave energy, a second similar wave guide having its broad sides parallel to the broad sides of said first wave guide and having two arms containing ends adapted for use as output terminals, said second wave guide being connected intermediate said two ends in overlapped relation to said first wave guide to form a T junction, means defining a rectangular aperture in the overlapped areas coupling the interior spaces of said first and second wave guides, said aperture having a length in a direction transverse to said second wave guide such that the full length thereof will transmit applied microwave energy while substantially less than the

full length thereof will prevent the transmission of such energy in any mode, a transverse metal plate terminating the other end of said first wave guide parallel to the center plane of said aperture and at a distance therefrom approximately equal to an odd quarter of the wavelength of said energy in the guide, a rotatable conductive shaft continuously and selectively adjustable through ninety degrees, said shaft being parallel to said first wave guide and lying across said rectangular aperture dividing it into two equal windows, and a pair of equal length conductive rods secured normally to said shaft and to each other and lying in said center plane each rod movable with said shaft partly to bisect a respective said window thereby partially interdicting said windows to microwave energy and concomitantly partially interdicting said arms.

6. A microwave switch comprising, a first rectangular hollow guide having an input terminal at one end adapted to be connected to a source of microwave energy, a second similar wave guide having broad sides parallel to the broad sides of said first wave guide and having two arms containing ends adapted for use as output terminals, said second wave guide being connected intermediate said two ends in overlapped relation to said first wave guide to form a T junction, means defining a rectangular aperture in the overlapped areas coupling the guides, said aperture having a length in a direction transverse to said second wave guide such that the full length thereof will transmit applied microwave energy while substantially less than the full length thereof will prevent the transmission of such energy in any mode, a transverse metal plate terminating the other end of said first wave guide parallel to the center plane of said aperture and at a distance therefrom approximately equal to an odd quarter of the wavelength of said energy in the guide, a rotatable conductive switch shaft having two terminal positions spaced ninety degrees apart said shaft being parallel to said first wave guide and lying across said rectangular aperture dividing it into two equal windows, first and second conductive rods of equal length secured normally to said shaft and normally to each other in said center plane, in one terminal position of said shaft said first rod being positioned to bisect one of said windows and said second rod spanning said second guide and in the other terminal position of said shaft said second rod being positioned to bisect the other of said windows and said first rod spanning said second guide whereby one or the other of said arms is interdicted to microwave energy.
